(57) **CLAIM**

We claim the ornamental design for a tablet pouch with tether, as shown and described.

DESCRIPTION

FIG. 1 is a front elevational view of a tablet pouch showing our new design in a closed position;

FIG. 2 is a rear elevational view thereof showing belt loops and attachment connectors;

FIG. 3 is a right side elevational view thereof;

FIG. 4 is a left side elevational view thereof;

FIG. 5 is a top end view thereof;

FIG. 6 is a bottom end view thereof;

FIG. 7 is right side elevational view of the tablet pouch shown in an open position;

FIG. 8 is a left side elevational view of the tablet pouch shown in the open position;

FIG. 9 is a perspective view looking towards the rear, inside portion of the tablet pouch in the open position and showing a tether pocket recessed into padding, stylus slots attached along the wall of the front inside portion, tablet retaining straps extending diagonally across corner regions of the rear inside portion, and a connector loop with connector attached near the top end of the front inside portion;

FIG. 10 is a perspective view looking towards the front, inside portion of the tablet pouch in the open position and showing the stylus slots, tether pocket, connector loop with connector, and retaining straps; and,

FIG. 11 is a left side and front perspective view showing the tablet pouch in the open position showing the tether pocket recessed into the padded area and a coiled connector strap attached to the connector loop; and where objects illustrated in broken lines are not part of the claimed design and are shown to illustrate exemplary components of the tablet pouch.
